UNITED STATES PATENT OFFICE.

HENRY EICHBAUM, OF NEW YORK, N. Y., ASSIGNOR OF TWO-THIRDS OF HIS RIGHT TO FRANK O. HERRING, JOHN FARREL, AND ELIJAH T. SHERMAN, OF SAME PLACE.

BURGLAR-PROOF SAFE.

SPECIFICATION forming part of Letters Patent No. 224,409, dated February 10, 1880.

Application filed June 26, 1879.

To all whom it may concern:

Be it known that I, HENRY EICHBAUM, of the city, county, and State of New York, have invented certain new and useful Improvements 5 in Burglar-Proof Safes, whereof the following is a specification.

The said improvements relate to the structure of the door and jamb and the means respectively of hanging, adjusting, and securing 10 or bolting the door.

I adopt a form whereof the sides and back are composed of a series of domed oblate arches, terminating in very short curves, united at the junction of the back and four sides. 15 The front is formed on a similar plan and provided with an opening shaped to furnish a jamb or seat for the door.

A ring of ductile metal is embedded in the jamb for an abutment to the bolts, which are 20 thrown out behind it in bolting the door. A ring or frame of ductile metal is anchored in the door, on which a frame is secured that carries the bolt-work. This consists of segments having motion imparted thereto by 25 suitable means operated from a central spindle, and said bolts, by impinging against the inner surface of a part of the jamb forming the abutment for the bolts, are adapted to draw in the door in the act of bolting it.

30 The means of hinging the door are so constructed as to admit of dividing the weight of the door between the upper and lower arms of the hinges, and also aid in adjusting the door to the opening therefor in the front of the safe.

I have shown in the annexed drawings a safe embodying my improvements of the class usually made by casting in a mold, although 35 part of my improvements are applicable to other kinds.

In said drawings, Figure 1 is a vertical section of the safe and door. Fig. 2 is a front view of the safe and door. Fig. 3 shows a face view, partly in section, of the inside of 45 the door. Fig. 4 shows the door partly in section, and as seen from the underside. Fig. 5 is a section of one-half of the door, showing the

means of fastening. Fig. 6 shows the arms for hanging and adjusting the door.

To enable others skilled in the art to construct my improved safe, I will proceed to describe the same.

Safes have been made by casting the main part or the whole of the body thereof in a mold; but when made square or rectangular 55 they have been incapable of successfully resisting the fracturing effect of heavy blows, as of a sledge-hammer, and when spherical or spheroidal in form they do not afford sufficient and convenient space within.

I have adopted a form for the body of the safe securing the arch or sphere, combined with the convenience and amount of space within the rectangular shape, and such form, although having an approximately rectangular 65 outline, if struck on the outside with a sledge the force of the blow will be received and resisted by the swelling and rotund surface which is presented at all points of the exterior, and such blow will either glance off or 70 be absorbed in and expended on such convex surface. This is illustrated in Figs. 1 and 2, where it will be seen that, however viewed, the back, sides, edges, and corners of the exterior all present convex surfaces at all sides 75 and corners.

Around the opening for the door I make the metal of increased thickness, (as I esteem this the weakest place,) and in the form of a heavy annular boss, A', in which the curves 80 of the adjoining sides of the body A terminate, and which projects beyond the opening for the door, so that when the door is in place the edge of the opening is perfectly protected from blows of a sledge-hammer.

The cast metal I use consists, preferably, of Franklinit or spiegeleisen, though any hard metal or alloy might be employed—such, for example, as white cast-iron, chilled iron, or cast-steel. I prefer spiegeleisen or Franklinit, as it 90 is cheap, and has proved itself by actual tests to be proof against the drill in the hands of burglars. From the fact that said metal is essentially inductile and practically incapable of be-

ing worked by cutting tools, I insert in the mold, previous to casting, a wrought-iron or steel frame or ring, C, which serves as part of the seat for the door, and being a ductile metal can be accurately turned and trued not only to fit the diameter of the door, but also on that surface which is presented to the interior of the safe where it forms the abutment for the bolts of the safe door. Such frame or ring also serves the very important purpose of giving the door, by means of its bolts, an effective hold on the body of metal in front of the bolts, as it extends into the boss A', and hence a much larger mass of metal would have to be ruptured to blow out or otherwise force away the door than if said ring were omitted.

B is the safe-door, made in this instance of hard cast metal; and to provide finished and accurate grooves for the bolts of the door and to have them carried by a material of great tensile strength, I employ a bolt-frame of a strong ductile metal—such as wrought-iron or steel—and made in this instance in the form of a ring, E; and to secure this bolt-frame to the door so that it cannot be forced therefrom by any of the usual means at burglars' command, I insert in the mold of the door, previous to casting, a ring of wrought-iron or steel, D, in such a position that when the door is cast part of the outside of the ring is left exposed, while the main portion is firmly embedded and anchored in the body of the door, and held therein partly through means of suitable projections or anchors d, forming part of the ring or affixed thereto, and partly by the strong contraction and adherence of the cast metal to the ring. This ring D, instead of being in one piece, may be in several, as its resisting power is not required to be exerted circumferentially, but transversely from the embedded to the exposed edge. To this ring I secure the bolt-frame aforesaid, or ring, E by cutting a heavy screw-thread upon its interior surface and a corresponding thread upon the exterior surface of the ring D, and screwing one upon the other, as shown in Figs. 4 and 5.

An equivalent mode of securing the bolt-frame E to the fixed ring or anchor D is to turn the outer surface of one and the inner surface of the other on a taper, as shown in Fig. 1, and then shrink the one over the other.

The door of the safe is arranged to swing, in opening and closing, on hinge-arms H I, secured to a shaft, G, working in hubs F F, affixed to or cast on the body of the safe. These arms are pivotally attached to hubs b' b² on the door, as follows: The free end of the arm H is tapped and fitted with a long screw, h, on the upper end of which is formed a bearing, that is fitted to turn freely in the hub b' on the door. By raising or lowering this screw h the door may be raised or lowered in adjusting it to move freely into and from its opening in the safe.

65 The bearing on the screw h may be set in a

core of Babbitt or like metal inserted in the hub b', to avoid grinding out the hub.

To make the upper arm, I, bear a proportion of the weight of the door, the spindle b³ or pivot of the arm I is keyed or otherwise made fast in the door, as shown at b², and the upper end of such spindle is threaded, and receives a nut, i, and washers above the arm I, whereby the door may be drawn toward the said arm and the lower arm, H, relieved of as much of the weight of the door as may be desired.

By the above several means the proper adjustment of the door is greatly facilitated, since the door may thereby be adjusted in height to correspond exactly with the opening therefor in the safe.

The door being very accurately fitted by grinding to the opening therefor in the safe, I also provide means for adjusting the door laterally as to such opening, as follows: By reference to the drawings, Figs. 2 and 6, it will be observed that the arms are much closer together at their hinged ends than at their free extremities, reaching obliquely upward and downward from their confined to their free ends. The door being massive and heavy and the arms of considerable length, they yield more or less to this weight, and the operation of such yield of the respective arms has a different effect on the door. Thus, if the weight of the door be carried entirely by the upper arm, I, the effect will be to straighten the arm toward a horizontal line, and so carry the door too far from the hinge; and if the weight be carried entirely by the lower arm, H, the effect is to bend the arm more, and so carry the door too close to the hinge. These effects are indicated in Fig. 6, where the arms (seen in full lines in their normal positions and in dotted lines in their strained positions) show that the giving down of the upper arm, I, carries the door outward along the arc w x away from the hinge, and the giving down of the arm H carries the door inward along the arc y z toward the hinge, so that, while the door may be adjusted in elevation by the screws in either arm, its adjustment laterally will depend upon the proportion of the weight of the door which each arm carries; for, after adjusting the door exactly in elevation, if, for instance, it is found necessary to set the door outward from the hinge in order to match the opening, it may be done by first relieving the lower arm of part of the weight and transferring it to the upper arm by turning out the screw h in the lower arm, the effect of which will be to cause the outer extremity of the upper arm to move down and out along the arc w x and the extremity of the lower arm to move up and out along the arc y z a part of the outer distance required, at the same time slightly lowering the door. Now, to restore the proper elevation of the door and carry it outward the remainder of the distance required, a further strain is put on the upper arm by screwing up the nut on

the spindle b^3 , the effect of which will be to raise the door to its proper elevation, and, while still further relieving the strain upon the lower arm and putting more upon the upper arm, cause their free extremities to move outward along their respective arcs, carrying the door with them the remainder of the distance required to match the opening laterally. If, on the other hand, after adjusting the door 10 in elevation, it should require to be set inward toward the hinge in order to match the opening laterally, the afore-described operation upon the screw h and spindle b^3 would be reversed.

15 To insure the movement of the door directly to its place and so that it will not bind in the opening, I have a guide, K, and a groove, J, in the jamb and door, respectively, and arranged transversely thereto. Such guide and 20 its groove are preferably located in the lower part of the jamb and under side of the door, and the guide K projects over the step in the edge of the door corresponding to the step in which the groove is cut in the jamb. The 25 guide is tapered on the entering end, so as to slip easily into the groove, and the guide holds the door in proper position until pushed home to its seat in the jamb, ready for bolting.

I will now describe my new means of fastening or bolting the door. I employ a series 30 of three or more bolts in form of segments, M, conforming to the shape of the door B, adapted to be moved radially outward and inward from and toward the center of the door in their bolting and unbolting action. These 35 segmental bolts M are preferably arranged to swing on pivots M' in a groove, L, formed to receive them in the periphery of the ring E or bolt-frame before mentioned. The bolts are of 40 ductile metal, such as wrought iron or steel, and are fitted closely into the groove L. This groove is so located on the door that its outer edge is nearly coincident with the inner and faced edge of the ring C in the jamb, but lacks 45 a little of being coincident when the door is shut. The bolts are actuated for setting them out and drawing them in by competent means through use of a spindle, P, which passes centrally through the door to the outside thereof,

50 and is there provided with a suitable handle, Q. The means I have shown consist of a number of radial screws, N, corresponding to the bolts, the outer extremities of which screws act directly upon said bolts, and on the inner 55 ends pinions O are mounted in bearings S, these pinions being turned in common from the spindle P aforesaid by a bevel-wheel, O', thereon.

The combination of the above parts or mechanism may be made in any suitable manner. The plan shown in the drawings, and which I have used with success, makes the pinions O serve also as nuts, the same being threaded within, and the inner ends of the screws N 65 adapted to work freely in such pins, while the

outer ends of the series connect directly with the bolts, as at m.

When the spindle P is turned in one direction the bolts will be forced out and engaged with that part of the jamb formed by the ring C, which is the abutment for the bolts, and when turned in the opposite direction the bolts will be retracted.

The door and the opening therefor in the safe being ground to an accurate fit, if the 75 door when closed be drawn tightly up to its place and held there, the insertion of wedges in the joint or the introduction of any explosive through the joint is rendered impossible. In order to accomplish this the entire circumference of the inner face of the ring C is beveled, as shown in Fig. 1, or, instead, all that portion of the bolting-segments M which corresponds thereto, or both, may be beveled, as shown, and so arranged with respect to each 80 other that when the bolts are set out from the door and engage the face of the ring C, while remaining partly in the groove L, the door will be acted upon for drawing it in around its entire circumference simultaneously. On 85 closing the door and turning the spindle P the bolts emerging from the groove L almost immediately engage the inner surface of the ring C, and a further rotation of said spindle draws the door inward in the manner afore- 90 said and securely fastens it.

The junction of the door with the safe thus made and with true and accurate surfaces forms a joint so close that the introduction of 95 wedges or explosives is rendered impossible.

The operation of the bolts is to be checked or controlled by locking mechanism, which may be of any kind desired.

T are lever-handles attached to screws set 100 in the arms H I, and adapted to be forced against the body of the safe to start the door out (after the bolts are retracted) preparatory to opening the door.

Having thus described my improvements, I 105 desire to have it understood that many of the details may be varied without affecting the nature and substance of the invention.

I claim as my invention—

1. A cast-metal safe-door having a bolt-frame anchor of ductile metal embedded therein. 115
2. In combination, the cast-metal safe-door with a bolt-frame anchor embedded therein and a bolt-frame secured to such anchor. 120
3. In combination with the safe-door, the bolt-frame anchor and the bolt-frame or ring E, grooved on its periphery, for the reception of suitable bolts. 125
4. In combination with the safe-door, the bolt-frame anchor, the grooved bolt-frame, and the bolts M, pivoted therein, substantially as specified. 130
5. The combination, with the safe-door having a grooved bolt-frame, of a series of three or more segmental bolts and a corresponding series of radial screws applied directly there-

to, each provided with a pinion, and all adapted for operation from a central spindle.

6. In combination with the safe-door and radially-moved segmental bolts, the safe-body having the continuous frame or bolt abutment.

7. The combination of the continuous frame or bolt abutment and radially-moved segmental bolts having a beveled face or faces, as specified, adapted to co-operate for drawing in the door after closing it.

8. The combination, with the door, of the

hinge-arms H, I, reaching obliquely upward and downward, respectively, from their confined to their free ends, and provided with screws h and b^3 , whereby the door may be adjusted both laterally and in elevation, as set forth.

HENRY EICHBAUM.
